United States Patent Office

Des. 205,956
Patented Oct. 11, 1966

205,956

WING PULLEY

Guthrie Boyd Stone, Honeoye, N.Y., assignor to Stone
Conveyor Company, Inc., Honeoye, N.Y.

Filed Oct. 11, 1965, Ser. No. 87,406

Term of patent 14 years

(Cl. D41—1)

FIG. 1

FIG. 2

FIG. 4

FIGURE 1 is a plan view of a wing pulley embodying my new design;

FIGURE 2 is an end view thereof, the opposite end being similar thereto;

FIGURE 3 is an exploded section taken on line 3—3 in FIGURE 2 and with the retaining bolts removed; and

FIGURE 4 is a sectional view taken on line 4—4 in FIGURE 3 and illustrating the whole cross section of one of the wings of the pulley.

I claim:

The ornamental design for a wing pulley, as shown and described.
